UNITED STATES PATENT OFFICE

140,202

DESIGN FOR A WHEEL TRIM OR SIMILAR ARTICLE

Charles B. Aske, Jr., Detroit, Mich., assignor to Lyon, Incorporated, Detroit, Mich., a corporation of Delaware

Application August 18, 1941, Serial No. 102,925

Term of patent 14 years

(Cl. D14—30)

To all whom it may concern:

Be it known that I, Charles B. Aske, Jr., a citizen of the United States, residing at Detroit, in the county of Wayne and State of Michigan, have invented a new, original, and ornamental Design for Wheel Trim or Similar Article, of which the following is a specification, reference being had to the accompanying drawing, forming a part thereof, in which:

Fig. 1 is a side elevational view of a wheel trim showing my new design; and

Fig. 2 is a diametric sectional view of a wheel trim showing my new design, a wheel and tire being indicated in broken lines for illustrative purposes.

Fig. 3 is a fragmentary elevational view shaded to represent contrasting colored areas and a

highly polished chrome or like finished band, the dark area being represented by A, the relatively lighter area by B, and the chrome or like finished band by C; it being understood that similarly designated portions in the other drawing figures represent similar light and dark areas and a chrome band; and

Fig. 4 is an enlarged fragmentary detailed sectional view showing more clearly the disposition of the chrome band on the wheel trim.

In the several drawing figures the wheel trim of my design is shown in full lines.

I claim:

The ornamental design for a wheel trim or similar article, substantially as shown and described.

CHARLES B. ASKE, JR.
